[57] CLAIM

The ornamental design for a fuse block, as shown and described.

DESCRIPTION

FIG. 1 is a perspective view of a fuse block in accordance with the present invention;

FIG. 2 is a bottom view of the fuse block shown in FIG. 1;

FIG. 3 is a left side end view of the fuse block shown in FIG. 1;

FIG. 4 is a right side view of the fuse block shown in FIG. 1;

FIG. 5 is a top view of the fuse block shown in FIG. 1;

FIG. 6 is a front view of the fuse block shown in FIG. 1; and,

FIG. 7 is a rear view of the fuse block shown in FIG. 1.

The fuse block illustrated in the drawings includes a clear plastic cover that substantially encases the fuse area. This

cover is illustrated by the shadowed lines in the drawings.
